UNITED STATES PATENT OFFICE.

EUGENE ZUELLIG, OF HAMILTON, OHIO.

MOLDING RING.

Application filed February 26, 1927. Serial No. 171,253.

This invention relates to a molding ring for use in connection with Babbitt bearing pouring.

A very common form of ring employed for this purpose in machine shops and garages at the present time, is one which is made up of wooden half sections suitably connected together to operate as enclosures for the bearings while the Babbitt lining is being poured.

It is of course well known that the life of these ring sections is comparatively short. In fact, they are ordinarily used only two or three times when it becomes necessary to throw them away and substitute new ones. This is objectionable in that it requires considerable time in the cutting of new ring sections.

I propose to substitute a metallic molding ring enclosing structure which will aid in the pouring and will prevent leakage of the molten babbitt. Incidentally, the objection to the ordinary metallic closure, is that it does not provide snug contact with the end of the sections of the bearing. In most instances, the ends of the respective sections do not come together in a flush manner. Consequently, it becomes difficult to form a tight contact between the closure and the sections of the bearing. The result, is leakage of the molten Babbitt.

It follows that the principal object here is to provide a sectional metallic closure wherein an adjustable filler is provided so that an efficient closure may be had at all times regardless of the ends of the bearing section.

Briefly, the improved structure comprises a closure ring which is composed of hingedly connected half sections, one of the sections being solid or of one-piece construction, and the other section being composed of two parts, the inner one of which constitutes a so-called filler, and which is adjustable toward and from the adjacent section of the bearing.

The particular details and advantages will become more readily apparent from the following description and drawings.

50 In the accompanying drawings:—

Figure 1 is an end elevation of a connecting rod including stationary bearing sections and removable cap showing the improved closure associated with each part.

55 Fig. 2 is a side view of the same.

Fig. 3 is a detail elevational view of the follower and filler member.

Fig. 4 is a fragmentary detail sectional view of a portion of the part represented in Fig. 3.

Fig. 5 is a cross section taken approximately upon the plane of line 5—5 of Fig. 3.

In the drawings, the reference character 1 designates a portion of a connecting rod provided with a head 2 forming one section 65 of the bearing. The complementary cap is represented by the reference character 3, and as customary, this is bolted in place. As before pointed out, the average cap does not accurately match the bearing section 2 70 with which it is intended to cooperate. The result is that one or both ends of the cap usually terminate short of the end of the section 2 or extend beyond it. In either case, this produces an irregularity which, 75 when pouring a Babbitt bearing, makes it difficult to provide an efficient closure between the Babbitt closing ring in the sections of the bearing.

Obviously if a tight closure is not present, the molten babbitt will leak out. It follows that the improved closure ring which I have provided overcomes this in the following manner.

The closure ring or molding ring is designated by the reference character 4, and as previously indicated, it is composed of two half sections. The solid half section is represented at 5. The complementary section however, is composed of two parts 6 and 70 90 which, when in contact with each other, are of a combined thickness equal to the thickness of the section 5 (see Fig. 2). Plates 8 are fastened to the left hand ends of the parts 5 and 6 and these plates are 95 hingedly connected together as at 9, allowing the parts of the ring to be swung apart to fit over the shaft. The opposite ends of the parts 5 and 6 are provided with bifurcated lugs 10 and 11 with which the 100 retaining bolt 12 and wing nut 13 cooperates in an obvious manner.

The part 7 is of semi-circular configuration as represented in Fig. 3, and is connected to the part 6 through the medium of 105 finger bolts 14. This is accomplished as better represented in Fig. 4, wherein it will be seen that on one side and at circumferentially spaced points, this part 7 is formed with recesses into which rectangular plates 15 are 110

fitted and held by retaining screws 16. The bolt 14 is swivelly connected with the plate as at 17. It follows that by rotating the bolt, this part 7 may be moved toward or 5 from the part 6 in order to permit it to be brought into contact with the bearing section 3 as shown in Fig. 2.

At this time, I would direct attention to the fact that the opposite ends of the parts 10 7 are recessed on one side for reception of removable blocks 18 held in place by removable headed retaining pins 19. The pins extend through bores and also through rounded lugs 20 carried by the blocks as shown 15 plainly in Figs. 3 and 5.

From the foregoing description, it is obvious that the parts of the molding ring may be swung apart to fit around the shaft and then the section 5 can be swung up 20 against and in tight abutting contact with the bearing section 2 as shown in Fig. 2. Assuming however, that the bearing cap 3 is slightly shorter than the bearing section 2, it will be seen that an irregular surface 25 will be present. However, by making a separate adjustment of the adjustable part 7 of the upper half section of the ring, this part can be brought into contact with the end of the bearing cap 3. Thus the parts 30 5 and 7 together will operate as an efficient closure to permit pouring of the babbitt while preventing leakage.

In some instances, bearing caps are provided on the ends with projections or flanges, 35 and it is for this reason that I have provided a removable block 18, which, when taken out, provide clearance spaces to accommodate such projections.

It is thought that by considering the description in connection with the drawings, 40 it will be seen that I have evolved and produced exceptionally novel molding ring structures for the purpose specified, which is superior to the ordinary wooden rings

employed and which is efficient, in that it 45 can be accurately adjusted for forming a tight closure.

Persons skilled in the art to which the invention relates will undoubtedly be able to understand the construction and method of use, as well as the advantages after reading the foregoing description. Therefore, a more lengthy description is thought unnecessary.

While the preferred embodiment of the 55 invention has been shown and described, it is to be understood that minor changes coming within the field of invention claimed may be resorted to if desired.

Having thus described my invention, what 60 I claim as new is:

1. In a structure of the class described, a closure forming and molding ring for a bearing structure comprising an annulus composed of hingedly connected half sections, one half section being in turn composed of relatively stationary and adjustable parts, the adjustable part being movable toward and from the bearing cap, the parts of said last section being of a combined 65 thickness equal to the thickness of the complementary section.

2. A combined molding and enclosure forming ring for a bearing structure of the 75 class described comprising an annulus composed of a one-piece semi-circular section, and a two-part complementary semi-circular section, the two-part section embodying a relatively stationary part hingedly connected to said one-piece section, and a relatively 80 movable part adjustable toward and from the bearing to be treated, bolts carried by the stationary part and swivelly connected with the movable part, and separable end blocks fitted in recesses formed in the end 85 portions of said movable part.

In testimony whereof I affix my signature.

EUGENE ZUELLIG.
